UNITED STATES PATENT OFFICE

HOMER H. HECKMAN, OF DETROIT, MICHIGAN

METALLIC ELECTRODE HOLDER

Application filed November 19, 1926. Serial No. 149,343.

The present invention relates to electrode holders for electric welding and particularly to holders adapted to hold firmly but release quickly the metal rod used for supplying metal to the operation.

Heretofore, electrode holders of this type have been made but most of them are open to the objections of expense, complexity, difficulty in manipulating to release the stub end of the electrode, heating due to the resistance of the materials used, danger to the operator due to exposed conductors and others.

Among the objects of the present invention is to overcome most or all of these objections and produce a holder that will be economical and easy to produce and assemble.

Another object is a holder that will hold an electrode firmly and yet easily release it when necessary or desirable.

Another object is an electrode holder that will have sufficient current carrying capacity so it will not heat.

Still another object is a holder in which the danger of contact of the hand of the user with "live" parts is minimized.

With these and other objects in view as will readily appear to those skilled in the art the invention consists in the device as illustrated in the accompanying drawings and in such modifications and alterations therein as come within the scope of the hereunto appended claims.

Referring to the drawings,

Fig. 1 is a longitudinal section through the holder;

Fig. 2 is a top view of the same;

Fig. 3 is a section on line 3—3 of Fig. 1;

Fig. 4 is a top plan view of a modified form of the holder;

Fig. 5 is a longitudinal vertical section therethrough;

Fig. 6 is a section on line 6—6 of Fig. 5;

Fig. 7 is a section on line 7—7 of Fig. 5.

The device consists broadly of a pair of

45 spring pressed jaws, between which the elec-

trode (not shown) is held, a handle, and means for separating the jaws.

One of the jaws consists of a bar of copper 10 extending from the front end 11 of the device through to the rear end of the handle 50 12. The greater portion of this member consists of a flat sort of trowel shaped piece, being fairly wide outside of the handle 12, narrowing somewhat toward end 11 and tapering quite sharply into the front end of handle 12 55 so as to position the member in the opening in the handle. It may be and preferably is provided with a stiffening rib 13 for a portion of its length. The part of member 10 within handle 12 is somewhat smaller than the part 60 outside but should be sufficiently large to conduct the required current without heating.

The rear end of member 10 is formed into a socket 14 provided with ribs 15 on its outer surface and threaded internally to receive 65 the correspondingly threaded nipple 16 provided on the end of cable 17. This nipple 16 may be a short tube of metal soldered or otherwise secured to short portion of the cable 17 from which the insulation has been 70 removed.

The other jaw 20 consists of a flat piece of steel of about the shape of the upper surface of member 10 but somewhat longer to provide an upward bend 21 as indicated. This bent 75 portion is slotted as at 22 and extends into handle 12 to the front end of socket 14 which is undercut as at 23 to receive the end of member 20. It is preferred to place between the members 20 and 10, from the rear end to the 80 bent portion of member 20, a thin sheet of insulating material such as mica 24.

The parts 10 and 20 with the mica are preferably secured together by a bolt 30 near the front end of the handle 12 as shown.

The slot 22 is provided for the passage there through of a lever 35, pivoted on member 10 as at 36 and extending to near the front end of bend 21. The free end of lever 35 is provided with an insulating sleeve 37 and 90

extends back over handle 12 for a short distance.

Handle 12 is preferably of hard insulating material bored lengthwise as indicated. The greater portion of this bore should be large enough to pass socket 14 and ribs 15 but at the rear end should be smaller so that it may be broached to provide grooves for ribs 15. These ribs and grooves serve to prevent turning of the parts within handle 12 when putting in or taking out of nipple 16.

In the use of the device, after nipple 16 attached to cable 17 has been screwed into place it may be and preferably is covered with insulating tape to prevent accidental contact of the operator's hands therewith.

In the construction shown, it is preferred to leave open the space 40 above the members 10 and 20 in handle 12 to permit free circulation of air in the handle.

In the modified form of the device as shown in Figs. 4 to 7, the jaw member 110 extends into but not through handle 112, and at its rear end is provided with a transverse groove 99 providing means for attachment, through screw 98, of the copper thimble 97 soldered to the end of cable 96. Thimble 97 is of such length that the insulation 95 extends into handle 112 when the connection is made.

The rear end of member 110 is preferably of circular section as is also the thimble 97 and both members of such size as to fit snugly within ribs 94 formed within handle 112, thus providing air spaces 93.

As indicated in Fig. 5, the rear end of jaw member 120 does not extend through to the rear end of handle 112 but only a short distance within the front end to a shoulder 92 on member 110. The rear portion of member 120 will there be secured to member 110 by means of the screw 121 and bolt 122, a strip of mica 123 or other heat resisting material being interposed if desired.

As indicated, the front end of handle 112 may be recessed as at 113 to accommodate the rear end of member 120 and the head of screw 121.

As in the first described form, member 110 will be provided with a stiffening rib 114 and this may extend to the front end of member 110 as shown.

Having now described the invention and the preferred forms of embodiment thereof, it should be noted that the said invention is not to be limited to the specific details herein set forth and illustrated but only by the scope of the claims which follow.

I claim:

1. An electrode holder for electric welding comprising a tubular handle of insulating material, a pair of metallic jaw members secured together with insulating material between and extending into said handle, one of said members being composed of metal of high conductivity and sufficiently large cross

section to conduct without material heating the welding current and adapted to be connected to a source of current, the other of said members being flexible material and adapted to have its free end sprung away from the free end of the other member.

2. In an electrode holder comprising a pair of holding jaws, one of which is copper and the other of steel, means to insulate the steel jaw member for a portion of its length.
